(57) **CLAIM**

The ornamental design for a double-sided over door hook, as shown and described.

DESCRIPTION

FIG. 1 is a front, top left perspective view of a double-sided over door hook showing my new design;

FIG. 2 is a back, bottom right perspective view thereof;

FIG. 3 is a left perspective view thereof;

FIG. 4 is a right perspective view thereof;

FIG. 5 is a front perspective view thereof;

FIG. 6 is a rear perspective view thereof;

FIG. 7 is a top perspective view thereof;

FIG. 8 is a bottom perspective view thereof;

FIG. 9 is an exploded view of FIG. 1; and,

FIG. 10 is a view of FIG. 1 in an environment of use on top of a door.

The broken lines shown in FIGS. 1, 2, 3, 4, 5, 6, 8, and 9 illustrate portions of the double-sided over door hook that form no part of the claimed design; The additional broken lines shown in FIG. 10 are for purposes of illustrating environmental subject matter only and forms no part of the claimed design.

The linear surface shading lines are not surface ornamentation, but are illustrative techniques for the purpose of depicting contour only and form no part of the claimed design.
